CLAIM

The ornamental design of a writing instrument container, as shown and described.

DESCRIPTION

FIG. 1 is a top left front perspective view of a writing instrument container showing our new design;

FIG. 2 is an exploded top left front perspective view thereof;

FIG. 3 is a left side elevational view thereof;

FIG. 4 is a right side elevational view thereof;

FIG. 5 is the front elevational view thereof;

FIG. 6 is the rear elevational view thereof;

FIG. 7 is the top plan view thereof;

FIG. 8 is the bottom plan view thereof;

FIG. 9 is a top plan view with the roof removed and the hood in the open position; and,

FIG. 10 is a top plan view of a second embodiment of our new design, with the roof member removed and the hood in a closed position, all other views being identical to the first embodiment.

The crayons depicted by means of broken lines in FIGS. 2 and 9 have been shown for illustrative purposes only and form no part of the claimed design.
